ELECTRIC DISCHARGE DEVICE HAVING A LOW IMPEDANCE AT ACOUSTIC FREQUENCIES

Gerardus Josephus Marie Alsmann, Eindhoven, Netherlands, and Hendrik Jan Oskam, Minneapolis, Minn., assignors to North American Philips Company, Inc., New York, N.Y., a corporation of Delaware

Filed June 19, 1959, Ser. No. 821,578

Claims priority, application Netherlands July 8, 1958
5 Claims. (Cl. 313—226)

Our invention relates to a gaseous electric discharge device employing a cold-cathode as an active element. More particularly the invention relates to an electric discharge tube employing a cold-cathode and a gas filling consisting essentially of a noble gas of low atomic weight to which a noble gas of higher atomic weight is added for the purpose of decreasing the impedance at acoustic frequencies.

It is often desirable for gaseous discharge tubes in various circuits to have as low an impedance as possible at acoustic frequencies. This applies, for example to voltage stabilizers having gaseous discharge tubes since a voltage ripple of acoustic frequency must be smoother as much as a slow variation in voltage. Also, for example, in a telephone exchange having switching tubes with or without an ignition electrode and which convey currents of acoustic frequency, such tubes must have as low an impedance as possible, since otherwise favourable proportioning of the various circuits is frequently impossible. In certain cases, this may also apply to series-discharge tubes in which an anode coacts arbitrarily with one of a plurality of cathodes, which tubes are employed in selecting or counting circuits.

An object of the present invention is to provide a tube having a cold cathode with a low acoustic impedance.

In a device according to the invention having a cold-cathode gaseous-discharge tube as an active element, which tube has a gas-filling substantially consisting of a noble gas of low atomic weight, to which a noble gas of higher atomic weight is added for the purpose of decreasing the impedance at acoustic frequencies, the noble gas of the lower atomic weight is helium, neon, argon or krypton and the balance of the mixture consists of neon and one or more of the gases argon, krypton and xenon, or of argon and one or both of the gases krypton and xenon, or of krypton with or without xenon, or of xenon only. The expression "active element" does not include a rectifier tube.

In tubes employed in a device according to the invention, the composition of the rare gas is dependent upon the object aimed at. Thus, in a voltage stabilizer, in addition to the operating voltage and the slope of the static characteristic of the voltage-stabilizing tube, only the impedance is important and not the restoring time after the extinction of the discharge. On the other hand, in a telephone exchange in which telephone currents traverse gaseous discharge tubes, it is not only the impedance of the discharge tubes which is important in addition to the static characteristic and the breakdown voltage, but also the restoring time after the extinction of the discharge. According to the invention, it has been found that, in order to obtain a short restoring time, the amount of the heavy rare gas must frequently be chosen larger than in other mixtures of lower impedance, since small amounts of heavy rare gases in the above-mentioned combinations result in the restoring time being lengthened, except in the case of He as the main gas.

Thus, in a tube according to the invention, which contains Ar and Kr, the percentage of Kr must lie upwards of 10% lest the restoring time is longer than in pure Ar.

The impedance-reducing effect of the admixtures may

2

be explained with the aid of considerations regarding charge transfer phenomena between ions and atoms.

In a discharge in a mixture of gases which substantially consists of a light rare gas and a small amount of a heavy rare gas, preferably the ions of the admixture are produced. This is attributable to the fact that the atoms of the heavy gas have an ionization voltage lower than that of the light gas and also a greater probability of ionization. However, in certain cases, ions of the light rare gas are also produced. The ions of the light main gas, upon impact with atoms of the admixture having a lower ionization voltage, can still transfer the charge to them. The ions of the admixture, because of the low concentration of the atoms thereof, impact so little with atoms of the same or lower ionization voltages that they cannot substantially transfer their charge and hence retain their full velocity. On the other hand, in a pure rare gas, new ions or ions produced by transfer of charge constantly impact with neutral atoms, whereby each time the charge is transferred so that the velocity on the average remains low. Consequently, the result of the processes is that in a rare gas containing a heavier gas admixture, the mobility of the ions in the dark room of Crookes, which is substantially a measure of the impedance, is considerably greater than in the case of pure rare gas. As a result thereof, the impedance of the mixture is lower because of its greater mobility of the ions than in the case of pure rare gas.

The invention will be described with reference to the 30 accompanying drawings, in which:

FIGS. 1 and 2 show tubes with which measurements were effected;

FIG. 3 shows a relay tube on which measurements have been carried out;

FIG. 4 shows a voltage-stabilizing tube on which measurements have been carried out;

FIGS. 5 to 11 show graphs of results obtained in the measurements.

Referring now to FIG. 1, in a glass bulb 1 there are 40 arranged two circular molybdenum plates 2 and 3 each of 15 mms. in diameter with a distance of a few millimetres between them. Connected to the bulb 1 is a horizontal tube 4 to which a plurality of small glass vessels 5, each closed by a spherical capillary tube 6, 45 is connected. The spherical capillary tubes 6 may be opened by means of a steel pellet 7. Each glass vessel 5 is filled with an exactly proportioned amount of rare gas or a mixture of rare gases. The bulb 1 is also filled with a pure rare gas. At a given current strength between 50 the electrodes 2 and 3, the impedance of the discharge space at several frequencies is now measured successively in the pure rare gas and after certain amounts of heavy rare gas have been added thereto from the vessels 5. The pressures prevailing in the vessels 5 must be equal to the 55 pressure in the bulb 1, since otherwise variations in pressure may occur and impede proper judgement of the results.

In FIG. 2, the cathode is constituted by a molybdenum cylinder having a diameter of 12 mms. and a length of 60 20 mms., the centrally-arranged anode being a molybdenum rod having a diameter of 2 mms. and a length of 25 mms.

In FIG. 3, the bulb of the switching tube is indicated by 10. A nickel cathode 12 and a nickel anode 13 are 65 pinched between two mica plates 11. The cathode is activated with a mixture of alkaline-earth oxides 14. The anode and the cathode each have a width of 4.5 mms. and a length at right angles to the plane of drawing of 8.5 mms., while the spacing between them is 2.75 mms. Arranged at each end of the cathode, at a distance of 70 0.2 mm. thereof, there is arranged an auxiliary anode wire 15 having a thickness of 0.3 mm. The electrodes

are connected to pins 16 by means of supporting wires.

FIG. 4 is a perspective view, partly open, of the bulb 17 of a stabilizing tube, the base of which contains a plurality of pins 18. Two slightly-curved molybdenum plates 19 and 20 are fitted on the pins 18 with a spacing of 6 mms. The plates measure 40 x 30 mms. and have a thickness of 0.2 mm. each. The pressure is 7 mms. of mercury.

In FIGS. 5 and 6, the impedance Z in ohms of the tube shown in FIG. 1 is plotted in the complex plane, that is to say, the real part of the impedance X along the horizontal axis and the imaginary part Y along the vertical axis wherein $Z=X+jY$. FIG. 5 shows the results measured for a current strength of 2 ma. and FIG. 6 for a current strength of 3.5 ma., wherein the line A applies to pure argon, the line B to argon and 5% of xenon, the line C to argon and 10% of xenon, and the line D to argon and 20% of xenon. The distance between the electrodes is 8 mms. and the pressure is 8 mms. of mercury. The numerals specified indicate the frequencies in c./s. at which the measurements were carried out.

FIGS. 5 and 6 clearly show that the addition of 5% of xenon to argon considerably decreases the impedance at both 2 ma. and 3.5 ma. If the percentage of xenon is increased to 10% or 20%, the imaginary part Y of the impedance further slightly decreases and from the curves an increase of the real part seems apparent. However, the latter phenomenon is the result of an additional effect which may be prevented by slightly increasing the total pressure, since as a result of the admixture, the normal current density varies slightly so that at this current strength and pressure the discharge can start to burn slightly abnormally and, as appears from a comparison of FIGS. 5 and 6, the real part of the impedance with abnormal burning (3.5 ma.) is larger than in the normal range (2 ma.).

The choice of the percentage of xenon in a given tube is dependent inter alia upon the desired restoring time which for higher percentages of xenon may lie below that of pure argon.

FIGS. 7 and 8 show the results of a series of measurements with argon-krypton mixtures in a tube as shown in FIG. 1, that is to say, again with a distance of 8 mms. between the electrodes and a pressure likewise of 8 mms. mercury column, FIG. 7 applying to a current strength of 2.5 ma. and FIG. 8 applying to a current strength of 3 ma. Curve E relates to pure argon, curve F to argon and 12.25% of krypton, and curve G to argon and 24% of krypton. From the specified values it clearly follows that the material decrease in impedance by addition of 12.25% of krypton is retained, whereas if the percentage of krypton is increased to 24%, a small increase of the real part of the impedance attributable to additional effects as in the case of argon-xenon is obtained.

FIGS. 9 and 10 show the results of measurements carried out with the tube of FIG. 2 in neon-krypton mixtures at current intensities of 6 ma. and 11 ma. Curve H relates to 100% of neon, curve I to neon and 5% of krypton, and curve K to neon and 17% of krypton. In connection with these figures the following remarks may be made. By the addition of an amount of krypton to neon, the normal current density considerably decreases. The inductance of a gaseous discharge is then inversely proportional to pressure. If, for example, with 5% of krypton, the current density is again brought to the value of that of pure neon by increasing the pressure, the line I would lie even lower, but especially more to

the left, since the real part is smaller in the normal range of the discharge. Otherwise, in designing a tube, the current density chosen greatly depends upon the life desired, especially if in contradistinction to the measuring tube, use is made of an activated cathode.

In connection with the foregoing it may be mentioned that the effect of the addition of krypton to neon upon the impedance is much stronger than the effect of the addition of krypton to xenon or argon. Nevertheless a strong decrease in impedance is not limited to neon-krypton mixtures, since helium upon addition of even small amounts of neon up to an optimum at about 5% also provides a greatly decreased impedance. In addition, this mixture has still other differing properties, since precisely at very low percentages of neon an appreciable shortening instead of a lengthening of the restoring time occurs.

With regard to the tube shown in FIG. 3, it is to be noted that measurements have revealed that in this tube also an impedance-reducing influence of krypton upon argon occurs. In connection with the desired decrease in restoring time, the optimum percentage of krypton lies between 15% and 20%.

FIG. 11 shows the results of measurements carried out with the voltage-stabilizer tube of FIG. 4, in which line L applies to a current strength of 7.5 ma. with 100% of argon and line M relates to a filling of argon and 5% of xenon at the same current strength. Lines N and P apply to the same fillings, but at 10 ma. The slope of the static characteristic of the tube in the region of from 1 to 15 ma. was, on the average, not more than 20 ohms.

While we have thus described our invention with specific examples and applications, we do not wish to limit thereto as other modifications and applications will be readily apparent to those skilled in the art without departing from the spirit and scope of the invention as defined in the appended claims.

What we claim is:

1. In an electrical system of the type including a source of electrical signals and utilization means therefor, an electron discharge device interconnecting said source and utilization means, said device comprising an envelope, a cold cathode, an anode, a first noble gas selected from the group consisting of helium, neon, argon, and krypton, and a second noble gas for reducing the impedance of said device at acoustic frequencies admixed with said first noble gas, said second noble gas having an atomic weight greater than that of said first noble gas and argon.
2. An electron discharge device as claimed in claim 1 in which the second noble gas is xenon.
3. An electron discharge device as claimed in claim 1 in which the first noble gas is argon which is admixed with 15 to 20% of krypton.
4. An electron discharge device as claimed in claim 1 in which the first noble gas is neon which is admixed with 15 to 20% of krypton.
5. An electron discharge device as claimed in claim 1 in which the first noble gas is argon which is admixed with about 5 to 20% of xenon.
